(57) **CLAIM**

The ornamental design for an electrical extension cord receptacle end, substantially as shown and described.

DESCRIPTION

FIG. 1 is a top plan view of the electrical extension cord receptacle end;

FIG. 2 is a right side elevation view thereof;

FIG. 3 is a left side elevation view thereof;

FIG. 4 is a bottom plan view thereof;

FIG. 5 is a front elevation view thereof;

FIG. 6 is a rear elevation view thereof;

FIG. 7 is a first upper perspective view thereof;

FIG. 8 is a second upper perspective view thereof;

FIG. 9 is a third upper perspective view thereof;

FIG. 10 is a fourth upper perspective view thereof;

FIG. 11 is a first lower perspective view thereof;

FIG. 12 is a second lower perspective view thereof;

FIG. 13 is a third lower perspective view thereof; and,

FIG. 14 is a fourth lower perspective view thereof.

The broken lines in the drawings are for the purpose of illustrating portions of the electrical extension cord receptacle end and environmental subject matter that form no part of the claimed design.
